TELEVISION STAND

Auburn G. Van Syoc, Sr., Belding, Mich., assignor to Rem
Corporation, Belding, Mich., a corporation of Michigan

Filed May 18, 1964, Ser. No. 80,037

Term of patent 14 years

(Cl. D33—3)

FIG. 1 is a perspective view of a television stand showing my design;

FIG. 2 is an elevational view taken from the right end in FIG. 1 and drawn to a reduced scale;

FIG. 3 is an elevational view showing the right side of the television stand of FIG. 1 on a reduced scale.

I claim:

The ornamental design for a television stand, substantially as shown.
